UNITED STATES PATENT OFFICE.

ALBERT H. SISSON, OF HIGH POINT, NORTH CAROLINA, ASSIGNOR, BY MESNE ASSIGNMENTS, TO GEORGE H. FORSYTH, OF CHICAGO, ILLINOIS.

METAL-SASH CUSHION.

1,237,712.

Specification of Letters Patent. Patented Aug. 21, 1917.

Continuation in part of application Serial No. 760,191, filed April 10, 1913. This application filed November 21, 1913. Serial No. 802,211.

To all whom it may concern:

Be it known that I, ALBERT H. SISSON, a citizen of the United States, residing at High Point, in the county of Guilford and State of North Carolina, have invented certain new and useful Improvements in Metal-Sash Cushions, of which the following is a specification, this application being a continuation in part of my application Serial Number 760,191, filed April 10, 1913.

The invention while relating to sash constructions in general has for its particular object the provision of an improved cushioning device in connection with a sash rail and stiffening lining of such shape and in such relation that they coöperate to effect a firm rigid construction and one in which the parts are readily assembled and securely held. Other advantages from the stand-point of mechanical construction and operation will be apparent to those skilled in this art.

In order that the invention may be readily understood a practical embodiment of the same is set forth in the accompanying drawing and in the description based thereon. As the invention is also capable of embodiment in other and varied constructional forms the drawings and description are to be construed as illustrative and not in an unnecessarily limiting sense.

In the drawing:

Figure 1 is a front elevation of one form of sash corner and cushion shown in assembled relation to the window frame which is partially broken away;

Fig. 2 is a vertical section through the sash looking toward the lock;

Fig. 3 is a horizontal section taken on the line 3—3 of Fig. 1; and

Fig. 4 is a fragmentary view in vertical section showing a modified form of cushion strip.

Having reference particularly to Figs. 1 to 3 inclusive the sash rail 11 and stile 12 are shown as mitered at 13 and connected to form a sash corner. The sash members 11 and 12 are here shown as formed of sheet metal tubular in cross section having a re-entrant portion 14 forming a groove for the reception of glass 15 with suitable interposed packing 16. It is desirable both from the standpoint of economy of material and also to encroach as little as possible upon the

window opening that the rail and stile be as narrow as is consistent with strength and with the necessity of affording a proper support and bearing for the sash lock. Ordinarily the sash members are made wider than would be otherwise necessary for the reason that one, and usually the rail, must be made wide enough to accommodate the lock plate and lock. By the present invention I am enabled to reduce the width of the rail and stile to an inch or less and also to employ lighter material for the same.

In carrying out the invention I provide a lock plate 17 which is secured to the rail and stile advantageously by screws 18 extending through into a corner reinforcement hereafter described. This lock plate is angular in outline and preferably L-shaped, one leg extending longitudinally of each of the sash members for a considerable distance beyond the corner of the sash thus bridging the mitered joint between the members. The inner edges of the plate are deflected laterally toward the glass as indicated at 19 and fit snugly against the inner edges of both the rail and stile. The vertical leg of the plate also preferably has formed integral therewith by stamping a lift 20 which projects into the glass area of the sash. It will be observed that the outer edges of the lock plate 17 do not extend to the outer edges of the rail and stile but are sufficiently remote therefrom to clear the stop 21 and the sill 22 thus presenting for engagement with the stop and sill a plane surface throughout and not requiring the lock plate to be inset in the sash.

The snug fit of the deflected portions 19 of the lock plate over the inner edges of the sash members tends to effect a firm engagement of the parts thus materially assisting and relieving the screws 18 from undue strain. This result is further enhanced by the provision of a stud 23 formed integral with and projecting from the lock plate into engagement with a recess in the edge of the stile.

The plate is further supported by means of screws 24, 24 which have threaded engagement with the threaded interior of the screw headed sleeves 25.

In the form of construction illustrated the movable lock member is pivoted upon a screw 26 in the stile of the sash and com-

prises a finger piece 27 projecting adjacent to the lift 20 and also an angular plunger or extension 28 terminating in a hook nose 29 which is adapted to engage within a recess 30 of the frame 31 and to bear under tension of the spring 32 upon the inner wall of said recess so as to force the sash in the opposite direction and prevent rattling. In order to safe-guard the pivot screw 26 against turning a pin 33 is seated within the plate 17 and projects inwardly therefrom into engagement with the slot of the screw.

The lower edge of the rail 11 is provided with a reentrant dove-tail groove 34 adapted 15 to receive a correspondingly shaped clip 35 having seated therein a rubber cushioning strip 36 which bears upon the window sill 37 to prevent the entrance of the elements underneath the sash.

20 In order to provide a particularly rigid and efficient connection between the rail and stile at each corner of the sash and to strengthen the rail carrying the cushion a reinforcing lining 38 is provided which is 25 L-shaped in side elevation and substantially U-shaped in cross section, the U opening inwardly. The limbs of the U are curved inwardly at their extremities, as indicated at 39, so as to follow the inward curvature of 30 the sash members into the restricted space at each side of the glazing groove and terminating with their edges abutting against the walls of said groove as clearly shown in the drawing. Heretofore it has not been 35 usual to have the reinforcement extend into this space on each side of the glazing groove and the lateral strength of the reinforcement has been correspondingly limited.

That portion of the reinforcement 38 40 which extends into the lower rail to any desired extent is slotted as indicated in Figs. 2 and 4, so as to embrace the dove-tail groove 34 and the clip 35, the relative position of the two walls of the reinforcement being 45 maintained by a spacing bolt 40 extending transversely and rigidly joining the two walls.

Not only does the reinforcing lining 38 stiffen the side and edge walls of the rails 50 and stiles, but by reason of its extending into the space on each side of the glazing groove and also embracing the dove-tail groove within which the cushion strip is mounted it serves to stiffen the angular connections of the frame and assist in maintaining 55 the proper relation between the parts.

The provision of the dove-tail groove 34 for the reception of the clip 35 serves of itself to greatly stiffen the rail while the slotting of the base of the reinforcing lining 38 60 and the extension of the angular margins 41 thereof into the spaces alongside and beneath the overhanging walls of the dove-tail groove coöperate to effect a very rigid 65 and unyielding sash rail, stiffening the

same along the lower side where it sustains the shocks incident to closing of the window.

The clip 35 having been permanently clamped upon the correspondingly shaped tongue 42 of the cushion 37 is assembled 70 with the sash rail 11 by sliding the same longitudinally of the groove from the corner of the sash. The end of the clip may be slightly deformed as by springing the same outward to bind within the groove and prevent further sliding movement, or a drop of solder or other expedient may be employed for this purpose, although in practice no tendency to shift is manifested and no precautionary steps are found necessary to be 75 taken.

The form of the lower face of the cushion may be convex in cross section as in Fig. 2 or concave as in Fig. 4, but in either case I find the dovetail tongue and groove connection between the cushion and sash by means of the dovetail clips of great advantage and a distinct advance in the art.

I claim:

1. In sheet metal sash construction, the 90 combination with a hollow sash rail, and a cushion on the bottom thereof, of an interior reinforcing lining having its lower edge abutting the lower wall to vertically support the same against blows transmitted 95 through the cushion.

2. In sheet metal sash construction, the combination with a hollow sash rail having a groove formed in its lower face, and a cushion on the bottom thereof seated in the 100 groove, of an interior reinforcing lining laterally supporting the side walls and extending into the space at the side of the groove to vertically support the lower wall of the sash against blows transmitted through the 105 cushion.

3. In sheet metal sash construction, the combination with a rail and stile connected to form a sash corner and provided along 110 their inner edges with a groove, of an interior reinforcement comprising a lining extending into the closed space on each side of the groove, the rail having along its bottom a groove, and a cushion seated within the groove, the reinforcement extending also 115 into the space on each side of the cushion groove, substantially as described.

4. In sheet metal sash construction, the combination with a rail and stile connected to form a sash corner and provided along 120 their inner edges with a groove, of an interior angular reinforcement U-shaped in cross section with the limbs extending into the space on each side of the groove, the rail having along its bottom a dove-tail groove, 125 a dove-tail slide within the groove, and a cushion seated within the slide, the bottom of the U-shaped reinforcement cut away to accommodate the cushion groove and the lower edges of the reinforcement extending 130

into the space on each side of the reentrant walls of the cushion groove and interlocking therewith, substantially as described.

5. In sheet metal sash construction, the combination with a rail and stile connected to form a sash corner and provided along their inner edges with a groove, of an interior angular reinforcement U-shaped in cross section with the limbs extending into 10 the space on each side of the groove, the rail having along its bottom a dove-tail groove, a dove-tail slide within the groove, and a cushion seated within the slide, the bottom of the U-shaped reinforcement cut 15 away to accommodate the cushion groove and the lower edges of the reinforcement extending into the space on each side of the reentrant walls of the cushion groove and interlocking therewith, and a spacing member 20 spanning the space between the limbs of the cutaway portion of the reinforcement above the cushion groove, substantially as described.

6. The combination with a sash member 25 having in its edge a reentrant groove, and a

resilient cushion seated within the groove, of a reinforcing member disposed within the sash and having portions supporting the outer walls of the sash and also extending into the space alongside the reentrant groove 30 whereby to laterally support the walls forming the cushion seat, substantially as described.

7. The combination with a sash member having in its lower edge a reentrant dove-tail groove, and a resilient cushion seated within the groove, of a reinforcing member disposed within the sash and supporting the side walls of the sash and having portions extending along the lower wall into the 35 space alongside the reentrant groove whereby to laterally support the walls forming the cushion seat, substantially as described.

In testimony whereof I have hereunto signed my name in the presence of two sub- 40 45 scribing witnesses.

ALBERT H. SISSON.
